COMBINED BOTTLE, CAP AND NAIL
POLISH APPLICATOR

Lawrence Carter, 420 E. 72nd St.,
New York, N.Y. 10021

Filed Sept. 26, 1968, Ser. No. 14,499

Term of patent 3½ years

Int. Cl. D9—01

U.S. Cl. D9—10

FIG. 1

FIG. 3

FIG. 2

FIG. 4

FIG. 5

FIG. 1 is an elevational view of a combined bottle, cap and nail polish applicator showing my new design;

FIG. 2 is a bottom plan view;

FIG. 3 is an exploded perspective view;

FIG. 4 is a section view of the upper portion of the cap taken along lines 4—4 of FIG. 3; and

FIG. 5 is a section view of the lower portion of the cap taken along lines 5—5 of FIG. 3.

The stippling indicates contrasting surface texture.

I claim:

The ornamental design for a combined bottle, cap and nail polish applicator, as shown and described.
